UNITED STATES PATENT OFFICE.

EDWARD C. ROSENAW, OF FENNIMORE, WISCONSIN.

NON-REFILLABLE BOTTLE.

SPECIFICATION forming part of Letters Patent No. 741,374, dated October 13, 1903.

Application filed July 23, 1903. Serial No. 166,742. (No model.)

To all whom it may concern:

Be it known that I, EDWARD C. ROSENAW, a citizen of the United States, residing at Fennimore, in the county of Grant and State of Wisconsin, have invented certain new and useful Improvements in Non-Refillable Bottles, of which the following is a specification.

This invention has for its object to prevent the reuse of a bottle or like receptacle after being emptied without mutilation thereof to such an extent as to attract attention of the most casual observer, thereby protecting in a measure the purchaser and the party or concern putting up a particular brand of goods.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a vertical central section of the upper portion of a bottle or like necked receptacle, showing the invention applied thereto. Fig. 2 is a perspective view of the guard attachment. Fig. 3 is a perspective view of the valved closure disconnected from the shell or casing. Fig. 4 is a vertical central section of the guard or device for preventing refilling of the bottle.

Corresponding and like parts are referred to in the following description and indicated in all the views of the drawings by the same reference characters.

The guard attachment or protector comprises a shell or casing 1 and a plug or closure 2, the two parts being adapted to be fitted together in any practicable way. The shell or casing 1 tapers slightly at its lower end and is made conical at its upper end, and is preferably constructed of metal, such as iron or steel, the upper conical end being case hardened or tempered, so as to resist the action of a drill. Outlets 3 are formed in the upper portion of the shell or casing at the base of the conical end, and the liquid contents of the bottle pass off therethrough. Curved catches 4 are located at opposite sides of the shell or

casing and are connected therewith by springs 5, the upper edges of the catches being straight and the outer lower portions upwardly inclined or beveled to ride upon the edge of the neck 6 of the bottle or package 7 when pressing the guard attachment or protector into said neck after the bottle or package has been filled. The catches 4 are curved transversely 60 of the shell or casing, and the latter is recessed in its outer side to receive the parts 4 and 5 when pressed inward, as when forcing the protector home into the neck of the bottle.

The plug or closure 2 is centrally apertured 65 and is provided with a pendent nipple 8, upon which is fitted a cork or packing 9 to insure a close fit between the neck of the bottle and the plug. A valve 10 is arranged to close downward upon the plug 2 and cover 70 the opening or outlet therethrough and is normally held seated by a light spring 11, the tension of which is sufficiently delicate to permit the unseating of the valve when the bottle or package is tilted to draw off the liquid contents. After the bottle has been emptied the valve is held seated at all times by the spring 11, thereby precluding the refilling of the bottle. A plate 12 is arranged above the valve 10 and is connected to the plug 2 80 by posts 13, the latter having their lower ends let into said plug. Openings 14 are formed in the plate 12 to provide an outlet for the liquid when the bottle or package is tilted to pour off its contents.

The neck 6 is of an internal diameter to snugly receive the guard attachment, and its inner or lower portion is slightly contracted to prevent slipping or passage of the protector or device into the bottle. An annular groove or depressions 15 are formed within the neck at a point to receive the catches 4 when the device is pressed home into the neck, thereby providing a lock to prevent the withdrawal or removal of the guard after being inserted into the neck to a point admitting of the catches 4 springing outward into the groove or depressions 15. The bottle or package 7 is filled in the accustomed way, after which the protector or guard attachment is inserted into the neck and pressed therein until the catches 4 spring outward into the groove 15, thereby preventing removal of the device except by forcible means,

which would result in mutilation of the bottle and insure detection of an attempt to reuse the same. After the bottle has been supplied with the protector it is closed by means of a cork 16 and sealed and labeled in the usual way. The openings 3 and 14 are out of alinement, and the posts 13 are preferably in line with the outlets 3, and the end portions projecting beyond the plate 12 approach the inner ends of the outlets 3 and are adapted to receive a wire or other instrument inserted through said outlets in an attempt to reach the valve 10, thereby increasing the difficulty and rendering it almost impossible to tamper with the valve by means of a wire or other contrivance.

Having thus described the invention, what is claimed as new is—

1. In combination, a bottle or analogous necked receptacle, a valved closure arranged within the neck, a shell located above the valved closure and having its upper end made conical and hardened to resist the action of a tool and having outlets in its upper portion, and spring-actuated catches applied to said shell and adapted to enter a depression in the inner side of the neck to hold said shell in place, substantially as set forth.
2. In combination, a bottle or necked receptacle, a valved closure arranged therein, a shell or casing located above the valved closure and provided with outlets, means for securing the shell within the neck of the receptacle, a plate arranged within the shell, and means connecting said plate with the valved closure, substantially as described.

3. In combination, a necked receptacle, a valved closure having a pendent nipple, a packing surrounding said nipple and secured to the under side of the closure, a shell arranged above the valved closure, and means for securing the shell within the neck of the receptacle, substantially as set forth. 40

4. A guard attachment or protector for necked receptacles, the same comprising a 45 valved closure, a shell fitted to the valved closure and having depressions in its sides, curved catches, and springs connecting said catches to the shell, the springs and catches being adapted to enter the depressions in the 50 sides of the shell, substantially as set forth.

5. A guard attachment or protector for necked receptacles, the same comprising a plug having an opening therein, a packing applied to the lower side of the plug, a spring-actuated valve normally closing downward upon said plug and covering the opening therein, posts projected from the plug, a plate fitted to the posts and having outlet-openings, a shell secured to the plug and enclosing the valve, posts and plate and having its upper end made conical and hardened to resist the action of a tool and having outlets in the upper portion, and a lock device applied to the outer side of the shell for securing it in place, substantially as set forth. 55 60 65

In testimony whereof I affix my signature in presence of two witnesses.

EDWARD C. ROSENAW. [L. S.]
